INVENTOR.
A. Nah. Gray. Woodward

BY

Clayton E. Wyrick
ATTORNEY.

UNITED STATES PATENT OFFICE.

ALVAH GRAY WOODWARD, OF DETROIT, MICHIGAN.

COLLAPSIBLE CRATE.

Application filed April 28, 1924. Serial No. 709,416.

To all whom it may concern:

Be it known that I, ALVAH GRAY WOODWARD, a citizen of the United States, and residing at Detroit, county of Wayne and State of Michigan, have invented a new and Improved Collapsible Crate, of which the following is a specification.

This invention relates to collapsible crates, and has for one of its objects the provision of a crate which, when collapsed, forms a box with closed walls of a size materially less than that of said crate.

Another object is to provide a crate which is adapted to collapse without resorting to any hinge connections between the several walls of the crate or between said walls and the crate bottom.

The above and other objects will be apparent from the following description wherein reference is made to the accompanying drawings, illustrating a preferred embodiment of my invention.

Figure 1 is a perspective view of the crate.

Figure 2 is a vertical sectional view of an end portion of the same taken on line 2—2 of Figure 1.

Figure 3 is a front view, partially in vertical section, of the box formed by collapsing of the crate.

Figure 4 is a perspective view of one of the wall forming units of the crate.

Figure 5 is a fragmentary vertical section, taken on line 5—5 of Figure 1, showing one of the connections between said wall forming units.

In these views, the reference character 1 designates the bottom member of the crate, said member being formed preferably of boards. Through the corners of said member are passed the headed lower ends of four two-part rods 2, 3 the two parts of said rods being pivotally connected as shown at 4, midway of the height of the crate. 5 designates a plurality of wall-forming units each consisting of a rectangular open frame, having apertures 6 at its corners to receive the rods 2, 3. The upper part 3 of each of said rods has its free end headed, as indicated at 7.

To the rear portion of the uppermost wall unit 5, a cover 8 is hinged as indicated at 9, a fastener 10, of any suitable construction

being provided to detachably secure said cover to the front portion of said unit. 55

When the units 5 occupy their spaced crate-forming relation, shown in Figure 1, spacer blocks 11 are engaged between said units to hold them properly spaced. It is preferred to provide four sets of these blocks, each set being rigidly secured to a bar 12. The four bars 12 are hinged as indicated at 13 to the bottom member 1 adjacent its corners, the hinge axes being parallel, so that when not in use, said bars may be 60 swung similarly down upon the bottom 1, adjacent to opposite side walls of the crate (see Figure 3).

The top and bottom faces of the blocks 11, converge slightly toward the free ends of 70 said blocks so that in swinging said bars to their upright positions of use, the blocks may be freely entered between the units 5. The free ends of the bars 12 are bent as indicated at 14 to form abutments which, when said bars are in upright position, engage above the top-most unit 5 holding the several units from any relative upward shifting. 75

In the use of the described receptacle as a crate, the bars 12 extend vertically adjacent the walls, and the spacers 11 project between the units 5 holding the latter uniformly apart a predetermined distance. The bent ends 14 of said bars engage above the units 5, resisting any force tending to force said units apart. The ends 14 are again bent terminally as indicated at 14a to engage in recesses in the bottom of the cover to positively prevent the bars 12 from swinging inwardly on their hinges. 80

The four two-part rods 2, 3 hold the units 5 from relative lateral movement, and the heads 7 of said rods assist in preventing said units from escaping endwise from said rods. 85

To collapse the described crate, the cover 8 is swung up sufficiently to release the upper ends of the bars 12, whereupon the latter may be swung upon their hinges 13 to the horizontal positions adjacent the bottom 1, seen in Figure 3. 95

This permits the units 1 to slide down on the rods 2, 3, to finally seat one upon another, thus producing closed walls. Under these conditions, the upper members 3 of the rods 2, 3, lie completely above the units 5 and may be swung to the horizontal posi- 100 105

tions, shown by Figure 3. The cover 8 is now closed down upon the receptacle and fastened, and separation of the units 5 vertically is positively prevented by the down-turned rod parts 3.

It is evident that the inclined top and bottom faces of the blocks 11 facilitate their insertion between the units 5.

From the foregoing description it will appear that the device is very simple and efficient in operation, will not easily get out of order, and provides a device which accomplishes the objects described.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having thus described my invention, I claim:

1. In a crate, the combination with bars forming the walls of the crate, of spacers insertable between said bars, and members carrying said spacers pivotally secured to the crate bottom to permit a ready removal of said spacers from between said bars.

2. A crate having its side walls formed by open frames normally spaced apart and movable into engagement to transform the crate into a box.

3. In a crate a plurality of wall units each comprised by an open rectangular frame, a set of spacers removably engageable between said frames, and a member supporting said spacers adjustable to a non-use position within the crate to permit said frames to engage each other and to form a closed box.

4. In a crate, normally spaced bars forming the walls thereof, spacers normally holding said bars apart, members carrying said spacers adapting them for group removal from between the bars, and rods upon which said bars are slidable to engage each other

and to form closed walls, when said spacers are removed.

5. In a crate, bars forming the walls thereof, two part rods loosely connecting said bars the parts of said rods being pivotally connected, and spacers removably engageable between said bars, the bars being slideable downwardly to engage the lower parts of said rods when the spacers are removed and the upper parts of the rods being then adapted to swing on said pivotal connections to retain the bars upon the lower parts of said rods.

6. In a crate, a plurality of open rectangular frames forming the crate walls, sets of spacers normally holding said frames apart, and members carrying said sets of spacers, adapting them for group removal from between said frames.

7. In a crate, a plurality of open rectangular frames forming the crate walls, a bottom member, and means attaching said frames to said bottom adapting them for a movement from said bottom to a spaced relation or toward said bottom to a closed-wall relation.

8. In a crate, a plurality of open rectangular frames forming the crate walls, bottom and top members, the latter hinged to the top-most frame, means attaching said frames to said bottom adapting them for a movement from said bottom to a spaced relation or toward said bottom to a closed-wall relation, bars hinged to the bottom member of said crate and adapted to swing to positions adjacent opposite walls of the crate, and a set of spacer members carried by each bar engageable between said frame members to maintain their spaced relation, the cover member being engageable with said bars in its closed position to hold the bars in vertical position.

In witness whereof I hereunto set my hand.

ALVAH GRAY WOODWARD.
